UNITED STATES PATENT OFFICE.

ARTHUR L. HALLIDAY AND WILLIAM McCALLUM, OF YONKERS, NEW YORK, ASSIGNORS TO THE BIGELOW CARPET COMPANY, OF CLINTON, MASS.

DESIGN FOR A CARPET.

SPECIFICATION forming part of Design No. 14,882, dated March 11, 1884.

Application filed February 8, 1884. Term of patent 3½ years.

To all whom it may concern:

Be it known that we, ARTHUR L. HALLIDAY, of Yonkers, in the county of Westchester and State of New York, temporarily residing in 5 Paris, France, and WILLIAM McCALLUM, of Yonkers, in the county of Westchester and State of New York, have invented and produced a new and original Design for a Carpet,
of which the following is a full description,
10 in connection with the accompanying photograph, which represents a face view of our new design for a carpet.

This invention relates to a new ornamentation of the face of a carpet, oil-cloth, or analo-15 gous fabric.

In the accompanying photograph are represented the various parts which enter into our new design.

A is a group of flowers, containing also leaves a, below which is the oblong ornament 20

b and rosettes d and e. B C D are groups consisting of flowers and leaves. The background of the carpet is covered with small star-like ornaments and rosettes.

I claim—

25 The design for a carpet, the same consisting of the figures A B C D a b d and e, substantially as shown.
